INVENTOR

Joseph Goldsmith, Jr.
BY HIS ATTORNEY
John L. Levy

UNITED STATES PATENT OFFICE.

JOSEPH GOLDSMITH, JR., OF CHICAGO, ILLINOIS.

HAIR-CURLING DEVICE.

1,400,812.

Specification of Letters Patent. Patented Dec. 20, 1921.

Application filed December 22, 1920. Serial No. 432,406.

To all whom it may concern:

Be it known that I, JOSEPH GOLDSMITH, Jr., a citizen of the United States, and a resident of the city of Chicago, county of Cook, and State of Illinois, have invented a certain new and useful Improvement in Hair-Curling Devices, of which the following is a specification.

This invention relates to a hair curling or crimping device and has for its object to provide a device of this character which receives and retains the hair and aids in producing a curled or waved appearance of the hair.

15 This object is attained by means of my device, which consists generally of a strip of flat resilient material bent upon itself to form a pair of opposing arms which receive, grip, press and crimp the hair between them, 20 a strand of hair usually being spirally wound on one of these arms and an improved arrangement being provided by means of which the ends of the arms may be detachably locked together.

25 A further object of my invention is to provide a device of this character in which the two arms can be readily locked together so that they cannot inadvertently separate while the device is in use and a still further 30 object of my invention is to provide a locking device for the two arms which has no protruding points or ends to injure the hair or the head.

With these objects and other objects which 35 may hereinafter appear in view, I have devised the particular arrangement of parts hereinafter set forth and more particularly pointed out in the claims appended hereto.

Reference is to be had to the accompanying drawing forming a part hereof in which—

Figure 1 is a plan view of my improved hair curling device in its closed position.

Fig. 2 is a section view on the line 2—2 of Fig. 1 looking in the direction of the arrows,

Fig. 3 is a bottom view of the ends of the spring arms showing the device for detachably locking the same together.

Fig. 4 is a side elevation of the device in 50 its open position, and

Fig. 5 is a sectional view on the line 5—5 of Fig. 1 looking in the direction of the arrows.

Throughout the various views of the drawings similar reference characters designate similar parts.

In the preferred embodiment of my invention, as illustrated in the accompanying drawing, the hair curling device is preferably constructed of a continuous strip of 60 flat, resilient material transversely folded upon itself to form a loop 1 and a pair of oppositely disposed normally separated spring arms 2 and 3. The arm 2 is provided at its end with a tapered portion bringing 65 the end down to a point 4 and the end of said point is bent laterally or upwardly to form a projection 5 which acts as a locking member to be hereinafter referred to.

The other arm 3 is provided with a locking device in the nature of a slidable sleeve member 6 which forms a combined locking device and guard member for the ends of two arms 2 and 3. This guard member is provided on its upper face with a raised 75 crown portion 7 which is centrally situated and of substantially the same contour or shape as the tapered end 4 of the arm 2. It will be seen that when the guard member is held over the end of the arm 2, the tapered 80 portion 4 of said arm fits into the crown portion 7 on the guard whereby lateral movement of the arm 2 is avoided. The under face of the guard member 6 is cut away or recessed as at 8. The guard member 6 is 85 slidable on the end of the arm 3 and the sliding movement of the same thereon is restricted by means of a pair of spaced-apart stops 9 and 10. The stops 9 and 10 are in the nature of elongated protuberances formed 90 by distorting or forcing outward the material of the spring arm 3. As the under face of the guard member 6 is cut away as at 8, the guard member is thus provided with a narrow portion 11 which lies between the 95 two stops 9 and 10 and permits the sliding movement of the guard member 6 on its arm 3.

The crown portion 7 of the guard member 6 is provided with a perforation or opening 100 12 with which the laterally extending projection 5 on the end of the arm 2 engages.

In using my improved hair curling device a strand of hair is wound spirally about the arm 2 and the arms 2 and 3 are pressed together while the slidable guard member 6 is in the position shown in dotted lines in Figs. 1, 3 and 4. When the two arms are brought together the guard member 6 is moved to a position so that it abuts against 110 the stop 9 and slides over the end of the arm 2. The tendency of the arms 2 and 3

to spring apart causes the projecting end 5 on the arm 2 to snap into engagement with the opening 12 on the guard member 6, as disclosed in Fig. 2, thus holding the two arms together securely. To release the arm 2 the two arms 2 and 3 are pressed together adjacent their ends so that the sleeve may be slid over the end of the arm 2 and the arms then spring apart to the position disclosed in Fig. 4.

While I have shown the projection 5 at the end of the arm 2 in the nature of an upturned or laterally bent tip thereon, it will be understood that any type of projection 15 may be formed on said arm by distorting or forcing outward the metal therein or in any other way. The opening 12 in the guard member 6 may also be varied in shape or size to suit the projection formed on the arm 2.

From the foregoing it is obvious that my invention is not to be restricted to the exact embodiment shown but is broad enough to cover all structures coming within the scope of the annexed claims.

What I claim is:

1. A device of the class described comprising a hair curler having a pair of resilient arms, a slidable guard on one of said arms adapted to be moved to overlie the end 30 of the other arm, the guard having an opening and a projection extending from one of the arms adapted to extend into said opening.

2. A device of the class described comprising a hair curler having a pair of arms, a slidable guard carried by one of said arms, an opening in said guard and a projection 35 on the other arm adapted to enter said opening when the guard is moved over said arm.

3. A device of the class described comprising a hair curler having a pair of arms, an apertured guard member movable on one of said arms, a projection on the other arm

adapted to be received in the aperture in 45 the guard member to cause a locking engagement between the arm and the guard member.

4. A device of the class described comprising a hair curler having a pair of arms, 50 a guard member slidably mounted on one of said arms and movable over the other arm, a projection, and an aperture for receiving the same to establish a locking means between the guard member and the 55 arm over which it is moved.

5. A device of the class described comprising a hair curler having a pair of flat resilient arms, a guard member slidable on one of said arms, a projection on the other arm, a central raised crown portion on the guard adapted to overlie the end of the other arm and the crown portion of the guard having an opening to receive said projection.

6. A device of the class described comprising a hair curler having a pair of arms, a guard member slidably mounted on one of said arms adapted to be moved to engage the other arm and hold the ends of 70 both of the arms together, the guard member having an opening, and a laterally bent end on the upper end of the last mentioned arm adapted to be received in said opening.

7. A device of the class described, comprising a hair curler having two flat resilient arms, a slidable guard member on one of said arms having a perforation, a pair of spaced-apart stops on said arm 80 adapted to restrict sliding movement of the guard member and a laterally bent end on the other arm adapted to enter into the perforation in the guard.

Signed at the city of Chicago, county 85 of Cook, State of Illinois, this 20th day of December, 1920.

JOSEPH GOLDSMITH, Jr.
